UNITED STATES PATENT OFFICE.

CLIVE M. ALEXANDER, OF TULSA, OKLAHOMA.

OIL BURNER AND OPERATION THEREOF.

Application filed February 26, 1926. Serial No. 90,755.

My invention relates to improvements in regulation of oil burners, and although of general utility is of special value and application in handling viscous fuel oils or fuel oils 5 containing large proportions of suspended solid or semi-solid matter.

In the conventional type of oil burner, a throttle valve is commonly employed in the fuel supply line for controlling the supply of 10 the liquid fuel. With fuel oils of high viscosity or with fuel oils containing much suspended matter, such throttle valves offer difficulties which will be apparent and which have been a serious handicap in the convenient and 15 effective utilization of fuels of this character. Clogging, for example, is a difficulty frequently encountered, and the operation also tends to be irregular and difficult of control.

A liquid fuel in utilization of which these 20 difficulties are encountered to a marked extent and to which my invention is particularly applicable is the residuum withdrawn from many of the so-called "cracking" processes which are in commercial use. This residuum 25 is usually of a heavy tarry nature and frequently contains large proportions of suspended matter, and consequently has been considered less desirable as a fuel than other more expensive fuel oils.

According to my invention, I control the 30 supply of liquid fuel to the oil burner by intermixing a gaseous medium with the fuel and regulating the proportion of this gaseous medium so introduced in admixture with the 35 fuel while causing this mixture to flow to the burner through a conduit of substantial length but of restricted cross-section. I have thus found it possible to eliminate any necessity for using throttle valves in the fuel supply line as I can effect control of the burner 40 simply by means of a valve in the line through which the gaseous medium is supplied. I thus secure convenient and ready control of the operation and can also secure improved 45 uniformity in operation, particularly when burning viscous fuels or fuels containing large proportions of suspended matter.

I am not entirely able to explain the results 50 I secure, although it seems that several factors are involved. With fixed conditions of pressure, the relative proportion of oil flowing to the burner would apparently be decreased by increasing the proportion of gas flowing

therewith through the conduit to the burner. The foam or emulsion of fuel oil and gas resulting from the intermixture may also have an increased resistance to flow which flow resistance varies with the proportion of gas present. In passing through the conduit between the point of introduction of the gaseous 55 medium and the burner, control of the flow resistance would afford control of the flow of fuel oil. Likewise, the gaseous medium may have a throttling effect at the point of introduction obstructing the flow of fuel oil similarly to a partially closed valve but without being subject to the difficulties encountered in the use of a valve of ordinary construction.

The exact method of introducing the gaseous medium in carrying out my invention 70 may be varied. It may, for example, be introduced through perforations or a peripheral slit in the conduit leading to the oil burner, and these perforations or this slit may be arranged to introduce the gaseous 75 medium in a direction normal to the axis of the conduit or at an angle inclined against the direction of flow of fuel oil through the conduit. Among the gaseous mediums useful in carrying out my invention are steam, air and 80 flue gases. Gases which take part in the combustion or gases which are inert therein, combustible or non-combustible gases, may be employed. Either wet or super-heated steam 85 may be used, for example, exhaust steam from an engine may be employed for the purposes of my invention. In any event, the gaseous medium is introduced into the conduit communicating with the burner at a point spaced from the point at which the conduit connects 90 with the burner so that the resulting mixture of gas and oil must flow through a substantial length of the conduit.

I will describe my invention further in connection with the accompanying drawings 95 which illustrate, diagrammatically and conventionally, apparatus embodying my invention and adapted for carrying out my invention. It will be understood that this further illustration and description are for the purpose of the exemplification of the invention and that the invention is not limited thereto.

In the accompanying drawings: 100
Fig. 1 represents in elevation, and partly in 105 section with parts broken away, an oil burn-

er assembly embodying the invention and adapted for operation in accordance with the invention.

Fig. 2 is an enlarged section of the mixing means illustrated in Fig. 1, and

Figs. 3 and 4 are similar sections of modified form of the mixing means.

Referring to the drawings, fuel oil is supplied to connection 5, the gaseous control medium through connection 6, and the gaseous medium for effecting the major part of the spraying or jetting of the fuel oil through connection 7. The fuel oil flows first through the mixing chamber 8 and then through the elongated conduit 9 to the burner proper being discharged through the opening 10 at the end of the conduit 9. The gaseous medium for spraying or jetting the fuel oil enters chamber 11 from which it is discharged to the burner nozzle 12 with the fuel oil escaping from the opening 10. The gaseous control medium enters the chamber 8 from which it is introduced into the conduit 9 through perforations 13. At this point this gaseous medium is intermixed with the fuel oil and the resulting mixture is confined within the conduit 9 and compelled to flow therethrough together to the point of discharge 10. The gaseous control medium is supplied under a pressure somewhat exceeding that maintained on the fuel oil and the supply of this gaseous medium may be controlled, for example, by the valve 14.

In the modified form of the mixing means illustrated in Fig. 3, the perforations 13^a, instead of being arranged to direct streams of the control medium in a direction normal to the axis of the conduit 9 as in Fig. 2, are arranged to direct streams of the control medium against the flow of the fuel oil. In the mixing means illustrated in Fig. 4, the gaseous control medium is introduced through a peripheral slit 15. This slit is arranged to introduce the control medium in a direction against the flow of the fuel oil, and the width of the slit is made adjustable by means of the collar 16.

In carrying out my invention in the apparatus illustrated in Fig. 1, the valve 14 is first opened and the control medium is admitted through connection 6 to the chamber 8 from which it escapes from the perforation 13 to the conduit 9. Valve 17 is then opened wide to avoid any throttling of the fuel oil and the fuel oil flows through connection 5 and then through conduit 9 in intermixture with the gaseous control medium entering through perforations 13. The flow of fuel oil to the burner is then controlled by regulating the valve 14 to control the proportion of gaseous medium introduced into the conduit 9 through the perforations 13. Additional gas for spraying and jetting the fuel oil and for controlling the operation of the burner, with respect to factors such as the length of

the flame, is admitted through connection 7 as may be required.

It will be apparent that I thus accomplish effective control of the supply of fuel oil and of the operation of the burner without throttling of the liquid fuel. The objections incident to the provision and operation of a throttle valve are thus eliminated by my invention.

I have successfully employed my invention in burning hydrocarbon tar containing from 60 to 70% of suspended carbon. The liquid, or semi-liquid fuel may be supplied under from 10 to 20 pounds gage pressure and the gaseous control medium may be supplied to the chamber of the mixing means under a pressure of from 50 to 100 pounds. In the burning of relatively thin liquid fuels, pressures as low as 5 pounds per square inch in the fuel may be used, and with very heavy or very viscous fuels pressures as high as 40 to 50 pounds per square inch or more may be employed with advantage. The pressures to be employed in any particular case will depend somewhat upon the nature of the fuel being burned, but in general higher pressures are employed with heavier or more viscous liquid fuels with a conduit of the same dimension connecting the mixing means and the burner proper.

I claim:

1. An improved method of controlling the flow of fuel oil to an oil burner, comprising supplying the fuel oil to the burner through an elongated conduit, introducing a gaseous medium into the conduit at a point a substantial distance from the point of discharge from the conduit in sufficient quantity so that any increase will result in a decrease in the amount of oil flowing through said conduit, whereby the gaseous medium and the fuel oil are intermixed and caused to flow in admixture through the conduit to the burner, and controlling the flow of liquid fuel by regulating the proportion of the gaseous medium caused to flow through the conduit in intermixture therewith.

2. An improved method of controlling the flow of fuel oil to an oil burner, comprising supplying the fuel oil to the burner through an elongated conduit, introducing a gaseous medium into the conduit at a point a substantial distance from the point of discharge from the conduit in sufficient quantity so that any increase will result in a decrease in the amount of oil flowing through said conduit, whereby the gaseous medium and the fuel oil are intermixed and caused to flow in admixture through the conduit to the burner, and controlling the flow of liquid fuel exclusively by regulating the proportion of the gaseous medium caused to flow through the conduit in intermixture therewith.

3. An improved method of controlling the flow of fuel oil to an oil burner, comprising

supplying the fuel oil to the burner through an elongated conduit, introducing a gaseous medium into the conduit at a point a substantial distance from the point of discharge from the conduit, and in a direction opposed to the flow of liquid fuel through the conduit, and controlling the flow of liquid fuel by regulating the proportion of the gaseous medium caused to flow through the conduit in intermixture therewith.

4. An improved oil burner assembly, comprising a burner nozzle and an elongated oil supply conduit adapted to discharge through said burner nozzle, means adapted to supply a gaseous medium directly to said burner nozzle and for spraying a liquid fuel with said gaseous medium, separate means for forcing a gaseous medium into said conduit at a point a substantially greater distance from the discharge end of said conduit than the distance between the discharge end of said burner nozzle and the discharge end of the said supply

conduit, and means for independently controlling the proportion of gaseous medium forced into said conduit.

5. An improved oil burner assembly, comprising a burner nozzle including means for spraying liquid fuel with a gaseous medium, an elongated oil supply conduit adapted to discharge to said burner nozzle, means for injecting a gaseous medium into said conduit at a plurality of points around the periphery of said conduit a substantial distance from the discharge end of said conduit and at an angle of at least 90° to the direction of flow of oil in the conduit approaching said injecting means, said injecting means being separate and in addition to the means for spraying the liquid with a gaseous medium, and means for controlling the proportion of gaseous medium forced into said conduit.

In testimony whereof I affix my signature.

CLIVE M. ALEXANDER.
